(57) **CLAIM**

The ornamental design for a resistance training device, as shown and described.

DESCRIPTION

FIG. 1 is a first perspective view of a resistance training device;

FIG. 2 is a top side view of the resistance training device;

FIG. 3 is a front side view of the resistance training device;

FIG. 4 is a right side view of the resistance training device;

FIG. 5 is a back side view of the resistance training device;

FIG. 6 is a left side view of the resistance training device;

FIG. 7 is a bottom side view of the resistance training device;

FIG. 8 is a second perspective view of the resistance training device;

FIG. 9 is a detailed view of portion 9 in the right side view of FIG. 4; and,

FIG. 10 is a detailed view of portion 10 in the first perspective view of FIG. 1.

The dash-dot broken lines shown in FIGS. 1, 4, 9, and 10 illustrate boundaries and indicators of the detailed portions and form no part of the claimed design. Furthermore, the dashed lines show portions of the resistance training device that form no part of the claimed design.

1 Claim, 10 Drawing Sheets
